UNITED STATES PATENT OFFICE.

CHARLES SUTTER, OF SURESNES, FRANCE.

GAS-CONTROLLING ATTACHMENT FOR GAS-OPERATED GUNS.

Original application filed March 25, 1921, Serial No. 455,701. Divided and this application filed February 27, 1922. Serial No. 539,517.

To all whom it may concern:

Be it known that I, CHARLES SUTTER, a citizen of the Republic of France, residing at Suresnes, Seine, France, have invented 5 certain new and useful Improvements in Gas-Controlling Attachments for Gas-Operated Guns; and I do hereby declare the following to be a full, clear, and exact description of the invention, such as will enable others skilled in the art to which it 10 appertains to make and use the same.

My present invention relates to improved means for regulating or controlling the relative amount of the powder gases delivered 15 from the bore of the gun to the motor piston in a gas operated gun.

The violence of the recoil of the motor piston would, of course, depend not only upon the work it is called upon to do, but 20 primarily upon the volume and pressure of the powder gases that escape from the barrel of the gun and enter the operating cylinder containing the motor piston.

In order to have the gun work with regularity, it is desirable to have the passages 25 clear through which the powder gases pass from the gun barrel to the cylinder, and substantially uniform in minimum cross section. There is a tendency, incident to 30 the operation of such guns, for these passages to become clogged up due to the solid matter carried along with the gases which adhere to the walls of the passage or passages and ultimately clog up the same.

35 My present invention relates not only to regulating initially the size of the passage, but also to provide a construction which will render it practicable to open up a new passage should the passage primarily in use 40 become clogged or choked for any reason, and to prevent any clogging up of such of the gas-ports as are out of action for the time being while the gun is in operation.

A further object of the invention is to 45 ensure a perfect gas-tight joint for preventing any leakage of the powder gases as they travel between the gas-port formed in the gun barrel and the gas-port formed in the nozzle head of the device.

50 My present invention is especially intended as a division of my application entitled Improvements in automatic machine guns, filed March 25, 1921, Ser. No. 455,701.

My invention will be more fully understood after reference to the accompanying

drawings, in which like parts are indicated by similar reference symbols throughout the several views, and in which:

Figure 1 shows a side elevation of part of the barrel portion of a gas operated gun 60 with the cylinder for the motor piston attached, parts being shown in section.

Figure 2 shows in side elevation, on a larger scale, the arrangement by means of which the amount of powder gases delivered 65 to the motor piston may be modified according to requirements.

Figure 3 shows a vertical longitudinal section of the parts shown in Figure 2.

Figure 4 shows a section along the line 70 4-4 of Figure 3, looking in the direction of the arrows, parts being shown in elevation; and

Figure 5 shows a section along the line 75 5-5 of Figure 3, looking in the direction of the arrows, parts being shown in elevation.

A represents the barrel of the gun provided with the usual bore *a* and the gas-port *a'* for supplying powder gases to the cylinder *B* for the motor piston *D*. 80

C represents the front sight of the piece.

E represents a band which preferably serves also as the carrier ring of the piece. This band is fitted over the barrel *A* and has the gas-port *e'* which registers with the gas-port *a'* from the bore *a*, and also has the gas-delivery port *e²* formed in the nozzle head *e³*. In the ring *E* is bored transversely 85 a cylindrical slot *e⁰* into which is fitted a plug *F*, provided with an angular opening *f* into which may be introduced a suitable instrument, such as a key, for rotating the plug when desired.

The plug *F* is formed with a number of ducts or passages, say three *f'*, *f²* and *f³*, the 95 diameters of which differ. The diameter of each duct may be chosen at will for the purpose of duly modifying the amount of the powder gases delivered to the motor piston. Those portions of the periphery of the plug 100 *F* from which the ducts *f'*, *f²* and *f³* do not debouch into the perforation *e⁰* may be reduced in diameter as shown at *f⁴*, *f⁵*, Fig. 5, so as to minimize friction, without however interfering with the proper fit of the 105 plug *F*.

The plug may be held in its adjusted position by means of a set screw *G*.

Assuming that it be desired to allow a relatively limited amount of the powder 110

gases to pass from the bore a through the intake gas-port a' to the delivery gas-port e^2 , the gunner selects say the duct f' and causes it to communicate with the two said 5 gas-ports. When the plug F is properly adjusted for the selected duct f' the gunner drives the set screw G home, so as to cause the opposite side of the periphery of the plug to make a gas-tight joint against the 10 opposite wall of the perforation e^o and effectively prevent any gas reaching the remaining ducts say f^1 , f^3 , while at the same time securing a continuous gas-tight connection between ports e' and e^2 on the one 15 hand and duct f' on the other.

On releasing the set screw G, the plug F becomes loose and may be adjusted to another position and is then tightened up again, while furthermore it may be readily 20 removed altogether for purposes of examination and cleansing, if and when required.

Finally, the device is, or may be, equipped with suitable marks which, being made visible from the exterior, will enable the gunner 25 at all times to see which of the ducts f' , f^2 , f^3 is in action. Such marks may, for instance, be formed as at 1, 2 and 3 on the outer face of the plug F, Fig. 2, so as to register seriatim with a mark o on the ring E.

I have shown three separate ducts or passages in the plug F for the flow of the powder gases, anyone of which may be used if desired; but obviously the number of said ducts may be increased or decreased at the 30 will of the manufacturer.

It will be obvious that various modifications might be made in the herein described construction, and in the combination and arrangement of parts which could be used 40 without departing from the spirit of my invention; and I do not mean to limit the invention to such details except as particularly pointed out in the claims.

Having thus described my invention what 45 I claim and desire to secure by Letters Patent of the United States is:—

1. In a gas operated gun, the combination, with the barrel and carrier ring delivering a portion of the powder gases from the bore 50 of the gun to the motor piston, of a revoluble plug having a series of transverse separate ducts in the walls thereof, both orifices of each of which ducts debouch from the periphery of said member.

2. In a gas operated gun, the combination, with the barrel and carrier ring delivering a portion of the powder gases from the bore 55 of the gun to the motor piston, of a revoluble substantially cylindrical plug having a series of transversely disposed separate ducts in the walls thereof, both orifices of each of which ducts debouch from the periphery of the said plug, and means for locking said plug in place in such manner as to provide 60 a continuous passage for the gases through 65

one of said ducts, while isolating the remainder of said ducts by means of a gas tight joint or joints.

3. In a gas operated gun, the combination with a barrel provided with a port for the escape of a portion of the powder gas, a cylinder fast to the gun, and a motor piston adapted to reciprocate in said cylinder, of a band secured on said barrel and provided with a downwardly projecting portion having a gas port therein registering with said gas port in the barrel and also a gas port opening into said cylinder, the said downwardly projecting portion of said band being also provided with a transverse cylindrical bore intersecting the gas ports provided in said band, and a substantially cylindrical plug provided with a series of transversely disposed ducts in the walls thereof, each adapted to form a continuous 75 passage with said last mentioned ports, and thus to permit the flow of gas from said barrel to said cylinder, through one duct only while the other ducts are completely masked.

4. In a gas operated gun the combination with a barrel provided with a port for the escape of a portion of the powder gas, a cylinder fast to the gun, and a motor piston adapted to reciprocate in said cylinder, of a band secured on said barrel and provided with a downwardly projecting portion having a gas port therein registering with said gas port in the barrel and also a gas port opening into said cylinder, the said downwardly projecting portion of said band being also provided with a transverse cylindrical bore intersecting the gas ports provided in said band, and a substantially cylindrical plug provided with a series of transversely disposed ducts in the walls thereof, each adapted to form a continuous 80 passage with said last mentioned ports, and thus to permit the flow of gas from said barrel to said cylinder, through one duct only while the other ducts are completely masked.

5. In a gas operated gun, the combination with a barrel provided with a port for the escape of a portion of the powder gas, a cylinder fast to the gun, and a motor piston adapted to reciprocate in said cylinder, of a band secured on said barrel and provided with a downwardly projecting portion having a gas port therein registering with said gas port in the barrel and also a gas port opening into said cylinder, the said downwardly projecting portion of said band being also provided with a transverse cylindrical bore intersecting the gas ports provided in said band, and a substantially cylindrical plug provided with a series of transversely disposed ducts in the walls 90 95 100 105 110 115 120 125 130

thereof, each adapted to form a continuous passage with said last mentioned ports, and thus to permit the flow of gas from said barrel to said cylinder, through one duct 5 only while the other ducts are completely masked, and means for visually indicating the position of said passages relative to said ports.

6. In a gas operated gun the combination 10 with a barrel provided with a port for the escape of a portion of the powder gas, a cylinder fast to the gun, and a motor piston adapted to reciprocate in said cylinder, of a band secured on said barrel and provided 15 with a downwardly projecting portion having a gas port therein registering with said gas port in the barrel and also a gas port opening into said cylinder, the said down-

wardly projecting portion of said band being also provided with a transverse cylindrical bore intersecting the gas ports provided in said band, and a substantially cylindrical plug provided with a series of transversely disposed ducts in the walls thereof, each adapted to form a continuous 25 passage with said last mentioned ports, and thus to permit the flow of gas from said barrel to said cylinder, through one duct only while the other ducts are completely masked, with means for locking said plug 30 at the desired position and for releasing same when desired, and means for visually indicating the position of said passages relative to said ports.

CHARLES SUTTER.
